(57) **CLAIM**

The ornamental design for a football helmet, as shown and described.

DESCRIPTION

FIG. 1 is a perspective view of the football helmet;
 FIG. 2 is a right side elevational view of the football helmet of FIG. 1;
 FIG. 3 is a left side elevational view of the football helmet of FIG. 1;
 FIG. 4 is a front elevational view of the football helmet of FIG. 1;
 FIG. 5 is a rear elevational view of the football helmet of FIG. 1;
 FIG. 6 is a top plan view of the football helmet of FIG. 1; and,
 FIG. 7 is a bottom plan view of the football helmet of FIG. 1. The broken lines shown in the drawings are included for the purpose of illustrating unclaimed portions of the football helmet and form no part of the claimed design.
